FREQUENCY MODULATOR

George L. Usselman, Port Jefferson, N. Y., assignor to Radio Corporation of America, a corporation of Delaware

Application June 18, 1940, Serial No. 341,119

8 Claims. (Cl. 179—171.5)

The present application concerns frequency modulators comprising oscillators with detuned oscillation circuits entrained by coupling to operate at the same frequency and means for modulating the oscillators to frequency modulate the resultant oscillations. In the present invention modulation is accomplished by modulating the element potentials of the oscillator tubes in the frequency modulator.

In describing my invention reference will be made to the attached drawings wherein:

Figs. 1 to 8, inclusive, each show a frequency modulator wherein two oscillation generators each including an electron discharge tube which would operate, when uninfluenced by the other, at different frequencies but which are entrained to operate at the same mean frequency. The oscillators are then modulated so that the more control passes from one to the other and in so passing varies the frequency of the oscillations generated. In the modification shown in Figs. 9 and 10, a third oscillator tuned to the said mean frequency of operation is used in the system.

Figs. 1 to 8, inclusive, show various forms of my invention. They all operate on the same fundamental principles. The frequency modulator stage B consists of two Hartley oscillator circuits comprising tubes V1 and V2. These two oscillator circuits tubes have their grids or their anodes cross-connected. Figs. 1, 3, 4, 5, 6, 7 and 8 show cross-connected grids in the frequency modulator. Signal oscillations are applied to the tube grids, anodes or auxiliary grids. Each side of the modulator is separately coupled at its output to stage C, not shown in Figs. 3 and 7. The latter is coupled to stage D (not shown in Figs. 3, 4, 6, 7 and 8) which consists of frequency multipliers or amplifiers, or both. These deliver their output to a load or antenna E. Fig. 2 is similar to Fig. 1, except that Fig. 2 shows the frequency modulator using cross-connected anodes. Fig. 3 shows the frequency modulator circuit B using pentodes or five element tubes instead of three element tubes. In Fig. 3 the control grids are cross-connected and the number 3 grids or shielded grids act as anodes for the oscillator circuits. The anodes of the tubes V1 and V2 are used for output coupling. In this circuit either the number 1 or number 3 grids may be cross-connected.

Fig. 4 shows the use of three element tubes V1 and V2 and neutralizing condensers in the frequency modulator circuit. In this circuit the grids are cross-connected and the audio signal oscillations are applied to the grids in somewhat

the same manner it is applied to the grids in Figs. 1, 2 and 3.

Fig. 5 is similar to Fig. 4 except that Fig. 5 shows a method of applying the audio signal oscillations to the anodes of the frequency modulator. Stage C of Fig. 5 shows the use of a twin screen grid tube V3' in stage C instead of two separate tubes. Fig. 5 also shows how a frequency regulating means, F, may be used to regulate the average frequency of the modulator carrier frequency by use of such apparatus as that described in U. S. Patents 2,044,749, 2,018,820 and 1,794,932. Means F operates condensers C3 and C4 to accomplish this purpose.

In the modification illustrated in Fig. 6, tubes of the screen grid type are used. The control grids of the tubes are cross-connected and differential anode modulation is used. In this modification as in all the prior modifications, it is important that individual oscillators be uncoupled or isolated except for the cross-connected electrodes. To do so, I provide shielding means S1, S2 between the oscillators and circuits. In all of the arrangements shown heretofore and hereinafter, grid or anode or screen grid modulation may be used.

Fig. 7 illustrates a modification wherein each separate oscillator comprises two electron discharge devices having their anodes and grids connected in push-pull oscillation generating circuits, the grids being cross-coupled to entrain the oscillators. In this modification differential anode modulation is accomplished although obviously the modulating potentials may be impressed on other electrodes.

In the modification shown in Fig. 8, the oscillators are each of the crystal controlled screen grid type with the grids cross-connected and the anodes modulated differentially. In principle, all of the modifications described hereinbefore, are, in general, the same.

In the arrangements shown in Figs. 9 and 10, an additional electron discharge tube oscillator V7 is used. In this modification the three oscillators are each coupled to the other to form what has been termed a "ring oscillator system." In these modifications it can be said, in general, that the principle involved in the prior modifications is also involved. That is to say, here the oscillators comprising tubes V1 and V2 are tuned to operate at frequencies on opposite sides of a mean frequency which is to be the carrier frequency in the absence of coupling between oscillators. The third oscillator comprising the tube V7 and its circuits is tuned to operate at the

carrier frequency. The oscillators are coupled and entrained so that as connected, coupled, and entrained they operate at a single frequency. In the presence of modulation which is applied to the control grids of tubes V1 and V2 in Fig. 9 and the anodes of the same tubes in Fig. 10, the oscillators cooperate to produce oscillations of a carrier or mean frequency equal to the frequency to which the oscillator including tube V1 is tuned, and the frequency of these oscillations swings in accordance with modulation. The output may be taken from the circuits of tubes V1 and V2 and impressed on separate electron discharge coupling systems as in Fig. 9 or the output may be taken from the circuit of tube V1 and supplied to a single electron discharge system as in Fig. 10.

Referring more in detail to Fig. 1 of the drawings, tube V1 has its anode 8 connected with an oscillatory circuit comprising condenser 10 and inductance 12. A point on this tuned circuit is connected to the control grid 18' of tube V2, this connection providing the coupling necessary to entrain the oscillator V1 and its circuits to the oscillator V2 and its circuits. The electrodes of tube V2 are connected in similar circuits. It is not believed necessary to describe these circuits and I have applied to the tube electrodes and circuit elements numerals primed corresponding to the numerals used in describing tube V1 and its circuits. Modulation is accomplished by impressing modulating potentials from a source A on the primary of transformer T and impressing the same from the secondary winding of T on the control grids 18 and 18' in phase opposition. The leads between the transformer secondary and the grids 18 and 18' include resistors 20 and 24.

The frequency modulated oscillations are supplied from each oscillator by way of leads 36 and 32 to the control electrodes 34 and 34' of coupling tubes V3 and V4. The anodes 36 and 36' of these coupling tubes are coupled together and connected to a parallel tuned circuit 40 which may supply the frequency modulated wave energy to an amplifier and/or frequency multiplier 46.

The circuit arrangement shown includes radio-frequency choking coils so designated, blocking condensers designated by the letters BC and bypass condensers designated by the letters BP. The function of these elements is known to those skilled in the art and it is believed unnecessary to describe the same in detail herein.

The modification shown in Fig. 2 differs from the modification shown in Fig. 1 in the following respects. The anodes 8 and 8' are cross-connected instead of the grid electrodes 18 and 18' and the biasing resistors 20 and 24 and associated bypass condensers BP have been rearranged because the grids in this arrangement are not cross-connected as in Fig. 1. In this modification variable condensers 50 and 50' are connected between the control grids and the tuned circuits 10 and 12 and 10' and 12' respectively in place of the coupling or blocking condensers BC of Fig. 1.

In the arrangement of Fig. 3 the grids are cross-connected as in Fig. 1 and the variable coupling condensers 50 and 50' are used as in Fig. 2. In Fig. 3, however, the electron discharge devices V1 and V2 are of the pentode type and the third grid 64, shielded by the second and fourth grids 60 and 62 connected together, serves as the anode of the oscillation generating circuits which, in this modification, are coupled by the

electron stream only to the anodes 8 and 8' and to the output circuit. In this modification, I have shown a resistance 70 tieing the plate 8 and 8' together. The output is derived from a tap on this resistance. This output may be supplied to an amplifier stage C comprising a single tube or two tubes and from the said stage to amplifiers and frequency amplifiers, etc.

The arrangement of Fig. 4 is described hereinbefore in connection with the prior figures and, in addition, I have provided in the arrangement of Fig. 4 neutralizing condensers N1 and N2 by means of which the separate electron discharge tubes V1 and V2 and their circuits are neutralized to further uncouple the same and isolate the same for individual operation except for the coupling obtained by the cross-connections between the grid electrodes 18 and 18'. The tubes V1 and V2 here, as in the prior modification, are shielded each from the other and from the following stages by shields S1 and S2.

In the arrangement of Fig. 5, I have replaced the stage C by a single electron discharge device V3 having two electrode systems one of which is coupled to the oscillation circuit comprising condenser 10 and inductance 12 and the other of which is coupled to the oscillation circuit comprising condenser 10' and inductance 12'. In this modification I have provided means in the form of variable condensers 80 and 80' connected with a frequency regulating system 84 the function of which is described more in detail hereinafter.

In the modification shown in Fig. 6, the control grids of the oscillator are cross-connected. Modulation is applied differentially to the anodes of the tubes and the tubes are of the screen grid type.

In the modification shown in Fig. 7, each of the oscillators comprises two electron discharge devices V1 and V5 and V2 and V6, each pair of devices having their anodes 8 and 8' and 81 and 81' connected in push-pull by the oscillation generating circuits comprising inductance 12 and condenser 10 and inductance 12' and condenser 10'. The grids 18 and 83 are connected to points on the inductance 12' while the grids 18' and 83' are connected to points on inductance 12. Modulation is applied on the anode electrodes 8 and 81. The remaining elements such as resistances, blocking condensers, radio chokes and bypass condensers have been designated by reference symbols used in the prior figures and need no further description.

In the modification shown in Fig. 8, the oscillators are of the piezo-electric crystal type. The tubes V1 and V2 have their anodes 8 and 8' and control grids 18 and 18' connected in oscillation generating circuits including crystals X1 and X2, respectively. That is, the crystal X2 is coupled between the grid 18 of tube V1 and the anode 8' of tube V2. The crystal X1 is coupled between the grid 18' of tube V2 and the anode 8 of tube V1. The anode 18 of tube V1 is coupled by a blocking condenser BC and radio-frequency choke to the control grid 34 of coupling and amplifying tube V3. A similar coupling is provided between the anode 8' of tube V1 and the control grid 34' of tube V2.

The piezo-electric crystal holders are variable to permit the frequency of the oscillations generated in the respective oscillation generator circuits to be varied the amount necessary to cause one oscillator, say tube V1 and crystal X1, to operate above and the other oscillator, say tube

V2 and crystal X1, to operate below the mean frequency at which they operate when entrained by cross-coupling the control grids 18 and 18'. Plate modulation in a differential manner is used in this modification by coupling the anodes 8 and 8' to the secondary winding of transformer T.

In the modification shown in Figs. 9 and 10, I have supplied an additional electron discharge device V1 of the screen grid type having an anode 100 connected in Fig. 9 to a tuned circuit comprising inductance 116 and condenser 114. A point on inductance 116 is coupled by condenser BC to grid 18 of tube V1. The grid 115 of tube V1 is coupled by a condenser BC to a point on inductance 12' and the grid 18' of tube V2 is coupled by a condenser BC to a point in the inductance 12.

In Fig. 10 the anode 100 of tube V1 is connected to a crystal X3 which is coupled to ground by a bypass condenser BP and to the grid 18 of tube V1. The grid electrode 104 of tube V1 is connected or coupled by a coupling condenser BC to a point on the inductance 12' of tube V2. The control grid 18' of tube V2 is coupled by a condenser BC to a point on the inductance 12 in the anode circuit of tube V1.

In Fig. 9 modulation is accomplished by modulating the potentials of the grids 18 and 18' of tubes V1 and V2 differentially. In the modification of Fig. 10 modulation is accomplished by modulating the potentials of anodes 8 and 8' of tubes V1 and V2 by coupling the same to the secondary winding of transformer T.

The modification shown in Fig. 10 is the same as the modification shown in Fig. 9 except that the crystal of Fig. 10 has replaced the tuned circuit comprising a capacity 114 and an inductance 116 of Fig. 9. These modifications are otherwise similar except that in Fig. 9 modulation is applied differentially to the control grids 18 and 18' through the secondary winding of transformer T. Moreover, in the modification shown in Fig. 9, separate coupling tubes V3 and V4 are used in stage C as in some of the prior modifications whereas in Fig. 10 the output is derived from a point on the circuit of tube V1 and is supplied to a single tube V8 in the stage C.

Figs. 4 and 5 will be used to describe the operation of this frequency modulator. It will be noted that each modulator consists of two oscillator circuits. These circuits are shielded from each other by shields S1 and S2 so that the only coupling they have to each other is through the cross-connected grids or the cross-connected anodes as the case may be. The input and output circuits are carefully arranged to cause no coupling between the two sides of the modulator.

In starting up the transmitter, proper steady cathode, grid and anode voltages are applied to the frequency modulator circuits. The two sides of the modulator oscillate at a steady frequency. Now, in order for the modulator to be able to vary the carrier frequency, or, in other words, to frequency modulate the carrier frequency, it is necessary to tune one half of the modulator to a certain amount below the carrier frequency and to tune the other half of the modulator substantially the same amount above the carrier frequency. This adjustment is made by means of tuning condensers 10 and 10'. The amount of adjustment depends on the desired frequency modulation band. Due to the method of coupling between the two halves of the modulator circuit, they will oscillate only on one frequency simultaneously. That frequency is determined by the rel-

ative amount of power supplied by each of the modulator tubes V1 and V2 and by the frequencies to which the modulator tank circuits are tuned. Some experience is required for adjusting these tank circuits. If they are adjusted for frequencies too far apart, the modulator will refuse to oscillate. One oscillator may be arranged to operate if considered alone at a frequency f_1 below the mean carrier frequency, the other at a frequency f_2 above the mean carrier frequency.

In operation, both sides (both halves) of the modulator oscillate approximately in phase. That is, the anode voltages of tubes V1 and V2 rise and fall about in phase and the grid voltages rise and fall about in phase but there is some phase difference between the two oscillators. However, if one tube, say V1, is biased to deliver more power than tube V2 then the output frequency will shift toward that for which the tank circuit 10 and 12 of tube V1 is tuned. If tubes V1 and V2 are biased so that tube V2 delivers more power than tube V1, then the output frequency will shift toward the frequency for which the tank circuit 10' and 12' of tube V2 is tuned. The amount of frequency shift and direction will depend on the direction and amount of bias and tank circuit tunings.

Now, it can be seen that by differentially changing the direct-current potentials of either the grids or the anodes with proper means, the carrier frequency of the transmitter can be frequency modulated in accordance with the signal oscillations. In other words, the signal oscillations will cause the modulator output frequency to shift above and below the average, or carrier, frequency in accordance with the signal oscillations. The amount of frequency shift will be proportional to the signal amplitude and the frequency of the shift will be the signal frequency.

This frequency modulator is one in which the usual amplitude modulation is balanced out; therefore, no distortion is caused from this source.

As stated previously, Figs. 1 to 4, inclusive, illustrate a method of operating the modulator by varying the grid potentials according to the signal oscillations from unit A through transformer T. Fig. 5 illustrates a method of operating the frequency modulator by varying the anode potentials according to the signal oscillations from unit A through transformer T.

The output from each half of the modulator is coupled to stage C in such a way that the two energies add but so that there is no coupling at this point between the two sides of the modulator. It is usual to amplify and multiply the frequency of the modulator output before it is radiated in antenna E.

It may be noted that in Figs. 4 and 5 neutralizing condensers N1 and N2 are used to neutralize capacity feedback on the same side of the circuit and that the grids are cross-connected through direct-current blocking condensers BC3 and BC4 to the opposite tank circuit. The same purpose is accomplished in Fig. 3 by the use of multi-grid tubes. This means that each half of the modulator depends on the opposite half for frequency control. Yet, the coupling is so tight that the modulator can operate simultaneously on only one frequency.

In Fig. 5, I have indicated a frequency regulation means F mechanically connected to auxiliary condensers C3 and C4 for regulating the average frequency of the modulator, and trans-

mitter to a required value. Unit F may be apparatus as described in my U. S. Patents 2,044-749, 2,018,820 and 1,794,932. To make the latter apparatus operate as desired, part of the modulator or transmitter energy is coupled to the detector input, as disclosed in Patent 1,794,932, and the automatic tuning gear, such as disclosed in Patent 1,794,932, or frequency correcting parts (20, 22, 24, 26, 42, etc.) are connected to auxiliary condensers C3 and C4 of the present invention. This would cause the apparatus to act as a frequency regulator in the present invention and it would tend to hold the transmitter frequency on line F_m and in band C—D of Fig. 2, Patent 1,794,932.

In Fig. 6, I have shown the frequency modulator and stage C using screen grid tubes V1, V2, V3 and V4. This circuit illustrates the use of anode modulation. In fact both anode and grid modulation were tried at different times on this circuit. The screen grids for each tube of the frequency modulator may or may not be modulated in audio phase with the anode, as desired. Fig. 6 shows each half of the modulator to be completely shielded from each other, which is very desirable for best results.

In all the modulator circuits that I have shown from Figs. 1 to 6, inclusive, each cross-connected oscillator has the tube connected across half of the tank circuit. This is equivalent to having a variable impedance connected across part of one branch of a parallel tuned circuit so that there is a tendency to change the resonant frequency of the tank circuit as the tube impedance is varied. This tendency is not appreciable but it is larger in the screen grid circuit, such as Fig. 6, than it is in the neutralized circuits. In order to overcome this detuning effect mentioned above, I have shown in Fig. 7, a frequency modulator in which push-pull oscillators are used. Fig. 7 illustrates the use of screen grid tubes in this circuit but three element tubes may be used by providing neutralizing condensers. This push-pull modulator overcomes the slight frequency modulation distortion present in Figs. 1 to 6, inclusive, due to each oscillator having a variable tube impedance connected across only one half of each tank circuit. Fig. 7 has a tube impedance connected across both halves of each tank circuit. These tubes in each oscillator have like variations in impedance as the modulation varies each oscillator potential differentially. In Fig. 7 no such frequency modulation distortion takes place. The circuit in Fig. 7 operates on the same general principles as the preceding circuits. The cross-connected oscillators of the modulator should be well shielded from each other, having only their grids or their anodes cross-connected. The frequency modulator may be considered as two cross-connected oscillators or as two cross-connected amplifiers, each amplifying oscillation energy from the other, in which their anode tank circuits are tuned differently or off frequency from each other. In order to get a frequency modulated carrier signal it is only necessary to differentially modulate the amplitudes of the oscillations in each oscillator. The amplitude of the sum of the energy output will be substantially constant but the frequency will be modulated.

The principle of cross-connected oscillators to compose this frequency modulator may be carried over into the use of quartz crystal oscillators, resonant line oscillators, and to the use of Haeff tube oscillators.

Fig. 8 illustrates a frequency modulator using

two cross-connected crystal oscillators. These crystals have their resonant curves partly overlapping. The crystal holder air gaps are made adjustable to get the desired frequency sweep for the frequency modulator. Fig. 8 shows the modulating potentials being applied to the anodes, but they could just as well be applied to the grids. Other crystal oscillator circuits may be used in this type of frequency modulator circuit.

Figs. 1 to 8, inclusive, show frequency modulators consisting of two cross-connected oscillators. It is possible to cross-connect or rather series-connect any number of oscillators or amplifiers in a closed ring.

In Fig. 9 I illustrate a somewhat different type of frequency modulator where this principle is carried out by using three oscillators (or amplifiers). Each oscillator is connected to and excited by the succeeding oscillator so that they are connected in a closed ring. All three oscillators oscillate on one frequency simultaneously. In this circuit two of the oscillators B1 and B3 are modulated while oscillator B2 is not modulated. In normal operation as a frequency modulator, one oscillator, say B2, is set at the desired fixed frequency or carrier frequency. This oscillator, B2, may be a coaxial line type of oscillator, a crystal controlled oscillator or any other desirable type of oscillator for holding an average frequency. Then the oscillator B1 is tuned say for a frequency slightly below that of oscillator B2 and oscillator B3 is tuned the same amount, say for a frequency slightly above that of oscillator B2. Now, according to tests, the frequency will be "pulled" toward that of the oscillator having the most circulating energy (current) in its tank circuit. Consequently, if oscillators B1 and B3 be differentially modulated so that alternately they have more oscillating current and deliver more controlling voltage than oscillator B2, then the frequency of oscillator B2 and the entire circuit will be shifted alternately to one side and to the other favoring the oscillator having the most power at that instant. When no modulation is present, oscillators B1 and B3 have equal power. Then oscillator B2, which has more controlling energy in its tank circuit and being of lower power factor (lower loss), will control the frequency. If oscillators B1 and B3 are differentially modulated according to the amplitude and frequency of the signal, then the modulator output will be frequency modulated according to the signal. The advantage of the modulator shown in Fig. 9 is that a better average or a more steady carrier frequency is produced. The disadvantage is that the circuit is more complicated.

Fig. 10 illustrates a frequency modulator having three oscillators in which the unmodulated oscillator B2 is a crystal controlled oscillator. It may be noted that in Fig. 9, I show grid modulation on oscillators B1 and B3 and the outputs of oscillators B1 and B3 are both combined in stage C. In Fig. 10, I show anode modulation on oscillators B1 and B3, while the output of oscillator B2 only is delivered to stage C.

The circuits in both Figs. 9 and 10 will give a frequency modulated current of substantially constant amplitude. As stated before, all oscillators and stage C should be well shielded from each other. These figures show the grids of each of the oscillator tubes being excited from the succeeding stage. This order can be reversed so that the grid of each of the oscillator

tubes is connected to and excited by the preceding stage.

It should be stated that the two oscillators which are modulated in Figs. 1 to 10, inclusive, should have substantially the same L-C ratio and should be identical otherwise to give linear frequency response. Oscillator B2 in Figs. 9 and 10 is the exception.

What is claimed is:

1. In a frequency modulation system, at least three oscillation generators each comprising a tube and a circuit tuned to a different frequency coupled to the tube electrodes, connections coupling corresponding electrodes of each tube to a point on the tuned circuit of another tube to connect said tubes and circuits in a ring connected oscillator operating substantially at a single frequency, and a circuit for modulating the impedances of two of said tubes differentially in accordance with signals.

2. In a frequency modulation system, a pair of tubes each having an anode, a cathode and a grid, a circuit tuned to a first frequency coupling the anode of one of said tubes to the cathode of said one of said tubes, a circuit tuned to a second frequency coupling the anode of another of said tubes to the cathode of the said other of said tubes, a third electron discharge tube having an anode, a cathode and a grid, a third circuit tuned to a frequency intermediate said aforesaid frequencies coupling the anode of said third tube to the cathode of said third tube, a coupling between an electrode in each of said tubes and a tuned circuit coupled with the electrodes of another of said tubes, connections for energizing the electrodes of said tubes whereby oscillations are produced in each of said tubes, and connections for modulating the impedances of two of said tubes in accordance with signals to thereby modulate the frequency of the oscillations produced by said tubes.

3. In a frequency modulation system, a pair of tubes each having an anode, a cathode and a grid, a circuit tuned to a first frequency coupling the anode and cathode of one of said tubes, a circuit tuned to a second frequency coupling the anode and cathode of the other of said tubes, a third electron discharge tube having an anode, a cathode and a grid, a piezo-electric crystal coupling the anode of said third tube to the grid of one of said pair of tubes, a coupling between the grid of the other of said pair of tubes and the circuit coupling the anode and cathode of said one of said pair of tubes, a coupling between the grid of said third tube and the circuit coupling the anode and cathode of said other of said pair of tubes, connections for energizing the electrodes of said tubes whereby oscillations are produced in said tubes and circuits, and connections for modulating the impedances of said pair of tubes differentially in accordance with signals to thereby modulate the frequency of the oscillations produced.

4. In a wave length modulation system, a pair of electron discharge tubes each having an electrode serving as an anode, a cathode and a control grid, a first circuit tuned to a first frequency, said first circuit having two terminals, a second circuit tuned to a second frequency, said second circuit having two terminals, a connection between a point intermediate the terminals of said first circuit and cathode of one of said tubes, a connection between a point intermediate the terminals of said second circuit and the cathode of the other of said tubes, a coupling between the

electrode serving as the anode of said one of said tubes and a point on said first circuit at one side of said intermediate point, a coupling between the electrode serving as the anode of said other of said tubes and a point on said second circuit at one side of said intermediate point thereon, a coupling between the control grid of said one tube and a point on said second circuit at the other side of said intermediate point thereon, a coupling between the control grid of said other tube and a point on said first circuit on the other side of the intermediate point thereon, a third tube having electrodes coupled to a circuit tuned to a third frequency in one of said last two named couplings, and means for modulating two of said tubes in push-pull relation at signal frequency.

5. In a wave length modulation system, a pair of electron discharge tubes each having an anode, a cathode and a control grid, a first circuit tuned to a first frequency, a second circuit tuned to a second frequency, means coupling the anode of one of said tubes to one of said tuned circuits, means coupling the anode of the other of said tubes to the other of said tuned circuits, means coupling the cathode of said one of said tubes to a point on said one of said tuned circuits, means coupling the cathode of the other of said tubes to a point on said other of said tuned circuits, means coupling the control grid of said one of said tubes to said other of said tuned circuits, means coupling the control grid of said other of said tubes to said one of said tuned circuits, a third electron discharge tube having electrodes coupled in a circuit normally operative at a third frequency in one of said last two coupling means, and means for modulating the impedances of two of said tubes differentially at signal frequency.

6. In a wave length modulation system, a pair of electron discharge tubes each having an anode, a cathode and a control grid, a first circuit comprising an inductance and a capacity in parallel tuned to a first frequency, a second circuit comprising an inductance and capacity in parallel tuned to a second frequency, connections coupling the anode of one of said tubes to the terminal of one of said circuits, connections coupling the anode of the other of said tubes to the terminal of the other of said circuits, connections coupling the cathode of said one of said tubes to a point on said one of said circuits, connections coupling the cathode of said other of said tubes to a point on said other of said circuits, connections coupling the control grid of said one of said tubes to a point on said second circuit, connections coupling the control grid of the other of said tubes to a point on said first circuit, and circuits for modulating the impedances of said tubes differentially in accordance with signals.

7. In a wave length modulation system, a pair of electron discharge devices each having an anode, a cathode and a control grid, a frequency determining reactance operating at a first frequency, a second frequency determining reactance operative at a second frequency, means coupling the anode of one of said tubes to one end of said first reactance, means coupling the anode of the other of said tubes to one end of said second reactance, means coupling the cathode of one of said tubes to a point on said first reactance and to a point of low radio frequency potential, means coupling the cathode of the other of said tubes to a point on said second reactance and to a point of low radio frequency potential, means coupling the control grid of said

one of said tubes to the other end of said second reactance, means coupling the control grid of the other of said tubes to the other end of said first reactance, means for modulating the impedances of said tubes differentially at signal frequency, a pair of amplifier systems each having a control grid and an anode, means coupling the control grids of said systems to said reactances, and means coupling the anodes of said tubes in parallel.

8. In a modulation system, a pair of electron discharge tubes each having an anode, a cathode and a control grid, a first circuit including an inductance tuned to a first frequency, a second circuit including an inductance tuned to a second frequency, means coupling the cathode of one of said tubes to a point intermediate the terminals of the inductance of said first circuit,

means coupling the cathode of the other of said tubes to a point intermediate the terminals of the inductance of said second circuit, means coupling the anode of said one tube to one end of the inductance of the first circuit, means coupling the anode of said other tube to one end of the inductance of the second circuit, means coupling the control grid of said one tube to a point on the inductance of the second circuit, 10 means coupling the control grid of said other tube to a point on the inductance of the first circuit, means for modulating the tubes differentially in accordance with signals, and means for amplifying the modulated oscillations comprising a pair of discharge systems having input electrodes tapped to said inductances and having output electrodes coupled in parallel.

GEORGE L. USSELMAN.
